UNITED STATES PATENT OFFICE.

BEATRICE H. GREENE, OF BINGHAMTON, NEW YORK, ASSIGNOR TO DOUGLAS V.
ASHLEY, OF BINGHAMTON, NEW YORK.

MOTION-PICTURE-FILM RENOVATOR.

1,156,994.

Specification of Letters Patent. Patented Oct. 19, 1915.

Application filed December 2, 1913. Serial No. 804,187.

To all whom it may concern:

Be it known that I, BEATRICE H. GREENE, a citizen of the United States, residing at Binghamton, in the county of Broome and State of New York, have invented certain new and useful Improvements in Motion-Picture-Film Renovators, of which the following is a specification.

My invention relates to an improvement in motion picture film renovators and repairers, and it has for its object to provide a simple and substantial mechanism or means for the removal of grease, dirt or other impurities which may collect on moving picture films from time to time when in use, and to enable a film to be handily repaired or patched at any given point without removal from the reel.

Another object of my invention is to provide a cleaning and renovating device for moving picture films that can be used as an attachment, or in conjunction with the usual moving picture machine.

With these objects in view, my invention consists in certain novel features of construction and arrangement of parts as will be hereinafter fully described and pointed out in the claims, reference being had to the accompanying drawings, in which—

Figure 1 is a side elevation of my device mounted ready for use. Fig. 2 is an end elevation of a part of my device showing the brushes and their gearing. Fig. 3 is a detailed view showing the cleaning box with parts in section. Fig. 4 is another detailed view showing the blotter rolls with parts in section. Fig. 5 is an end view of a part of my device mounted on platform. Fig. 6 is a side elevation of a part of my device showing the manner of adjusting the blotter rolls. Fig. 7 is a transverse section of one of the blotter rolls, and Fig. 8 is an end view of a part of my device.

The same reference characters denote like parts in each of the several figures of the drawing.

In carrying out my invention, I provide a suitable support, or platform A, which may be disposed between the usual film reels F, F¹, of a moving picture machine.

Mounted on platform A, I have the brushing device B comprising the frame 2, mounted on the base 3. In said frame 2, I have the brush rollers 4, mounted on shafts

5, 5¹ respectively. On the ends of shafts 5, 5¹ are the cog-wheels 6, 6 which mesh into each other.

On the opposite end of shaft 5, I have the pulley-wheel 7.

Mounted on platform A, also, and on a line with the brush cleaner B, I have the cleaning box C. Both the brush cleaner B and the cleaning box C are in alignment with the film reels. The cleaning box C comprises the body portion 8 and the lid 9. Slidably mounted within the body portion 8, I have the wood tension plate 9¹, supported by the coil springs 10, 10, resting on the bottom 11 of the body portion 8.

Resting on the tension plate 9¹, I have the pad mat 12 which serves to cushion, and resting on the mat 12, I have the cleaning mat 13. The tension plate and mats mentioned are slidably mounted within the body portion 8 so as to move up and down upon the springs 10, 10 when moved by pressure. On the body portion 8, I have mounted a lid 9 by means of hinges; the line of meeting between lid and body portion being on an incline as shown in Fig. 1.

Mounted within the lid 9, I have the pad mat 14 which is also a cleaning mat, and slidably mounted above pad mat 14 and within the lid, I have a wood filling 15.

Mounted in the top of lid 9, I have the threaded turn screws 16, 16 entering into threaded openings in the wood filling 15. Lid 9 is hinged to the body portion 8 by means of the hinges 17, 17 and held by clasps 18, 18.

The mats 13 and 14, may be of any suitable soft material, such as felt, eiderdown and the like. These mats may be impregnated with, or sprinkled with some cleansing substance preferably in liquid form.

Mounted also on platform A, and in alignment with the cleaning box C and the film reels hereinafter mentioned, I have the blotter D composed of the frame 19 resting on base 20.

Mounted within frame 19, I have the blotter rollers 21, 21¹, which are mounted on the shafts 22 and 22¹ respectively. The blotter rollers being formed of the body portion a, a¹, on which is mounted the blotter sheets b, b¹ respectively. These blotter sheets are composed preferably of ordinary blotting paper, or equivalent material. The

shaft 22 is slidably mounted within frame 19 by means of the sliding sockets 23, 23.

Mounted opposite each other on the sides of frame 19, I have the plates 24, 24 having in each a threaded opening, and mounted within the plates 24, 24, I have the thumb screw rods 25, 25, which have swivel connection with the sliding sockets 23, 23, mounted in opposite recesses 26, 26 in the sides of the body portion 19.

Within the body portions *a*, *a*¹ of the rollers 21, 21¹ of the blotter D, I have a recess 27 in each roller, and into this recess are extended the ends of the blotter surface, *b*, *b*¹.

15 The platform A is mounted on the usual reel platform E, on which are the usual film reels F, F¹, having the usual gear wheels *c*, *c*¹ and the crank *d*, and which film reels are mounted on the standards 28, 28 by 20 means of the shafts 29, 29¹. The end of shaft 29¹ has the usual thumb nut 30 and washer 31. On shaft 29¹ and between the thumb nut 30 and the washer 31, I mount the pulley wheel 32. On the reel platform 25 E and between the reels F, F¹ and out of alignment therewith, I mount the table G. On the surface of the table G, I have a mat 33, and at the edge of table G I have mounted by means of a hinge 34, the binder 35, 30 and on the opposite edge of table G, I have the clasp 36. On the pulley wheels 7 and 32, I mount the belt 37.

In the operation of my device, when I desire to clean a film, I insert the end of the 35 film H between the brush rollers 4, 4. I turn the crank *d* which moves film H through the brush wheels 4, 4 by means of the belt 37 and the gearing 6, 6, and so the film H moves on to the cleaning box C. I open the 40 lid 9 of the cleaning box C and place the film on the cleaning mat B and close down the lid. Again turning the crank *d*, I move the film H through the cleaning box C and between the mats 13 and 14 of the cleaning 45 box C, on to the blotter D. I then insert the end of the film H between the blotter rollers 21, 21¹ and turning the crank *d*, I move the film H on to the point of its connection with the intake reel F¹ where it is fastened in the 50 usual manner to the reel. I thus continue turning until reel F¹, winding on the film, until the entire film has passed through the brush rollers 4, 4, cleaning box C and blotter rollers 21, 21¹, and all impurities 55 removed from the surface of the same. When a film has become broken or needs patching or repairing, I place the film H upon the mat 33 on the surface of the table G, first opening the binder 35. I then close the 60 binder and fasten it with the clasp 36. The

film is thus firmly held in position for any work found necessary upon it.

It is obvious that in lieu of the blotter sheets on rolls 21, 21¹, I may use mats, and it is also obvious that the rolls 21, 21¹, may be positively driven, rather than by the friction of the passing film. By means of the springs 10, 10 in the cleaning box C the surface of the mats are thus brought into yielding contact with the surface of the 70 passing film. Also by means of the thumb nut 25, 25, I can adjust the space between the blotter rollers 21, 21¹ at any convenient distance to meet the requirements necessary for cleaning the film passing through. 75

Having thus described my invention, what I claim as new and for which I desire Letters Patent is as follows:

1. A motion picture film renovator mounted between supports for two film reels, one of which supports is provided with reel revolving means, said renovator comprising a pair of rotary cleaning brushes between which a film is adapted to be drawn when wound from one to the other reel and loose dirt removed, driving means between said revolving means and the brushes, a cleaning box in the line of travel of said film containing a yieldingly held mat and a positively adjustable co-operating mat for wiping both sides of said film, and a pair of co-operating absorbent rollers beyond the cleaning box for drying said film. 80

2. A motion picture film renovator mounted between spaced upright supports for two film reels, one of which supports is provided with reel revolving means, said renovator comprising a pair of rotating cleaning brushes, geared together, between which a film is adapted to be drawn when wound 85 from one to the other reel and loose dirt removed, driving means connected to said revolving means and one of said brushes, a cleaning box in the line of travel of said film containing a spring sustained lower 90 mat and an adjustable co-operating upper mat for wiping both sides of said film, means for varying the pressure between said mats, and a pair of co-operating rollers beyond the 95 cleaning box provided with removable absorbent coverings and adjustable to and from each other for drying both surfaces of 100 said film. 105

In testimony whereof I affixed my signature in presence of two witnesses.

BEATRICE H. GREENE.
